US00D880646S

(12) **United States Design Patent** (10) Patent No.: **US D880,646 S**
(45) Date of Patent: ** Apr. 7, 2020

(54) **ELECTRONIC PEST REPELLER**

(71) Applicant: **Tijun Gu**, Shenzhen (CN)

(72) Inventor: **Tijun Gu**, Shenzhen (CN)

(73) Assignee: **Shenzhen Fascent Technology Co., Ltd.**, Shenzhen (CN)

(**) Term: **15 Years**

(21) Appl. No.: **29/676,634**

(22) Filed: **Jan. 13, 2019**

(51) LOC (12) Cl. **22-06**

(52) U.S. Cl.

USPC **D22/120**

(57) **CLAIM**

The ornamental design for an electronic pest repeller, as shown and described.

DESCRIPTION

FIG. 1 is a front perspective view of the electronic pest repeller showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.
